TRANSFER APPARATUS

Edward J. Protin, Charleroi, Pa., assignor to
 Pittsburgh Steel Company, Pittsburgh, Pa., a
 corporation of Pennsylvania

Application December 28, 1934, Serial No. 759,445

4 Claims. (Cl. 198—20)

My invention relates to transfer apparatus, and more particularly to apparatus for transferring and handling tubes, bars, and the like.

The apparatus is shown in the drawings as employed for the transferring and positioning of tubes to and from pipe-threading machines, but it will be understood that it can be employed in connection with other types of apparatus such as cutting-off machines, etc.

5 One object of my invention is to provide an improved means for lifting and transferring tubes, one by one, from skids or a table, to a point at which they are to be operated upon, and thereafter discharging the tubes from the last-named 10 position.

Another object of my invention is to provide transfer mechanism for tubes and the like which will hold said tubes against undesired rolling movements, and wherein no tongs or grappling 15 members are required.

Still another object of my invention is to provide an improved arrangement of transfer mechanism and supporting rollers for tubes and the like.

25 One form which my invention may take is shown in the accompanying drawings wherein Figure 1 is a fragmentary plan view of the apparatus; Fig. 2 is an end elevation thereof; Fig. 3 is a view taken on the line III—III of Fig. 2, on 30 an enlarged scale, and Fig. 4 is a view taken on the line IV—IV of Fig. 3.

Stated generally, the apparatus comprises skids or tracks 6 of suitable number, depending upon the length of tubes or bars to be handled, and 35 also includes a series of lifters 7, rollers 8, tracks or skids 9, lifters 10, rollers 11, and skids 12. The purpose of the lifters 7 is to transfer tubes, one by one, from the tracks 6 to the rollers 8, and thereafter transfer tubes to the tracks 9.

40 The lifters 10 transfer the tubes to the rollers 11, and thereafter discharge them to the tracks 12.

As shown more clearly in Figs. 2 to 4, the tracks 6 are mounted on standards 14—15, the tracks 9 are mounted on standards 15—16, and the 45 tracks 12 are mounted on the standards 16 and

17. A rock shaft 18 is journaled on the standards 15, and a rock shaft 19 is journaled on the standards 16. The shafts 18 and 19 are periodically oscillated to effect vertical reciprocation of 50 the lifters 7 and 10, respectively, the lifters all being of the same form, and operated from their respective shafts in the same manner, so that a description of the operation of the lifters 10 by the shaft 19 will suffice also for a description of 55 the lifters 7.

The shaft 19 is provided with a crank 21 near each end that is connected to a piston rod 22. Each piston rod 22 extends into a cylinder 23, and is connected to the rear end of a suitable piston. Fluid pressure is admitted to the front 5 side of the piston through an opening 24 to effect rocking of the shaft 19 (Fig. 2) in a counter-clockwise direction, the weight of the lifters serving to return the piston to the position shown in Fig. 2, when the fluid pressure is released. 10

The shaft 19 also carries a crank arm 26 for each lifter 10. The lifters 10 have vertical sliding movement in the standards 16, and are supported at their lower ends upon the outer ends of the crank arms 26 that may be provided with 15 rollers, if desired. It will be seen that when fluid pressure is admitted to the cylinders 23, the shaft 19 will be rocked in a direction to raise the lifters 10 to the dotted line position shown in Fig. 4. 20 The shaft 18 and the lifter 7 are similarly operated from cylinders 28. Each of the lifters is provided with shoulder portions 29—30 that serve as stops for limiting rolling movements of the tubes, the surface between the shoulders 29 and 30 being inclined so that when the tubes are 25 picked up by this inclined portion of the lifters, they will roll against the seats 30. 20

A supply of tubes 32 is provided on the tracks 6 which are inclined toward lifters 7. Stops 33 are provided for limiting rolling movement of the 30 tubes, the stops being adjustable longitudinally of the tracks (Fig. 4), so that each forward tube 32 will be in proper position to be picked off by the lifters when the lifters are raised. For example, the stops 33 will be set further forwardly 35 for large tubes than for smaller tubes, so that the rear corners of the lifters will pass between the two front tubes.

When the lifters are raised from their retracted full-line position in Fig. 4 to the dotted line position, they will pick off the foremost tube, lifting it clear of the stops 33, and permitting it to roll against the seats 30. When the lifters are lowered, they will bring the tube to rest upon the 45 rollers 8 or 11 as the case may be.

The rollers are grooved or concave, the rollers 8 being aligned opposite to a threading or cutting-off machine 35, while the rollers 11 are aligned opposite to a similar machine 36. The 50 rollers are mounted upon brackets 37, and have screw-threaded studs which are engaged by adjusting nuts or hand wheels 38 that are supported on pedestals 39. Turning of the hand wheels 38 will bring the rollers to the proper elevation where 55

the pipes will be aligned with the machines 35 or 36.

When a pipe 32 is placed on the first set of rollers 8, it is released by the lifters 7 and can then be moved longitudinally of itself along the rollers 8 for a threading operation by the machine 35. It is then drawn back from the machine, whereupon the lifters 8 are again operated, at which time, the inclined surfaces 41 of the lifters will engage the pipe and move it to the track rails 9, whence it will roll to the next series of stops 33. During this discharging movement of the lifters 7, they will pick another tube from the tracks 6, so that upon reciprocation of the lifters, one tube will be discharged from the rollers and another tube will be deposited thereon, and the same operations will occur at the rollers 11 and the threading machine 36.

I claim as my invention:—

1. Transfer apparatus comprising a runway for tubes and the like, a stop member near the front end of the runway, a lifter normally positioned below the runway, a pipe-supporting seat on the lifter, sloping downwardly from the end of the runway and having a vertically-extending stop surface at the lower end of the sloping seat, and circumferentially recessed rollers positioned to receive a pipe when the lifter is lowered, the rear ends of the rollers extending rearwardly of said stop surface, and the mid portions of the rollers being disposed forwardly of said stop surface.

2. Transfer apparatus comprising a runway for tubes and the like, a stop member near the front end of the runway, a lifter normally positioned below the runway, a pipe-supporting seat on the lifter, sloping downwardly from the end of the runway and having a vertically-extending stop

surface at the lower end of the sloping seat, circumferentially recessed rollers positioned to receive a pipe when the lifter is lowered, the rear ends of the rollers extending rearwardly of said stop surface, the mid portions of the rollers being disposed forwardly of said stop surface, and a pipe-supporting seat on said lifter sloping downwardly and forwardly from said stop surface, and positioned to raise a tube from the rollers upon upward movement of the lifter.

3. Transfer apparatus comprising a runway for tubes and the like, a lifter normally positioned below the discharge end of the runway, means for raising the lifter to raise a tube from the runway, a tube-supporting seat on the lifter, sloping downwardly from the runway and having a stop surface at its lower end, and receiving members having recessed seats, the said seats having their deepest portions offset somewhat forwardly of said stop surface, but the seats being positioned to receive a tube when the lifter is lowered.

4. Transfer apparatus comprising a runway for tubes and the like, a lifter normally positioned below the discharge end of the runway, means for raising the lifter to raise a tube from the runway, a tube-supporting seat on the lifter, sloping downwardly from the runway and having a stop surface at its lower end, and receiving members having recessed seats, the said seats having their deepest portions offset somewhat forwardly of said stop surface, but the seats being positioned to receive a tube when the lifter is lowered, the lifter having a second pipe-engaging surface disposed forwardly of said stop surface and positioned to lift a tube from the said recess when the lifter is raised.

EDWARD J. PROTIN.
